UNITED STATES PATENT OFFICE.

ADAM PRIMAK, OF KENOSHA, WISCONSIN.

LOCK.

Application filed April 25, 1922. Serial No. 556,396.

To all whom it may concern:

Be it known that I, ADAM PRIMAK, a citizen of the United States, and resident of Kenosha, in the county of Kenosha and State of Wisconsin, have invented certain new and useful Improvements in Locks; and I do hereby declare that the following is a full, clear, and exact description thereof.

The invention relates to locks of a type having a plurality of tumblers therein adapted to be moved from locking position by a key.

It comprises a casing, a shackle having one of its arms rotatably secured in the casing and the other arm slotted to receive a tooth on a block. A plurality of aligned spring urged tumblers are provided received in recesses in a cylinder to unlock the device. A key is inserted in the slotted cylinder and lifted upwardly, moving the tumblers from the recesses. This permits rotation by the key of the cylinder, which, on sufficient rotation, is arrested by additional spring urged tumblers which are releasable by a lateral movement of the key. The release of these additional tumblers permits the withdrawal of the cylinder in the direction of its axis. On the withdrawal of the cylinder, the block and retaining tooth are removed, permitting the release of the shackle.

The primary object of the invention is the provision of a lock which is exceedingly complicated and difficult of operation for one not knowing the principle of operation. To unlock, it is necessary to lift the key, rotate the cylinder, lower the key, and then withdraw the key. Four distinct operations must be performed. This makes it very difficult to pick the lock. It does not suffice merely to lift or lower the tumblers, but a series of distinct operations must be gone through. There is no way to ascertain from the exterior of the lock the nature of the structure. At the same time, the construction is of such a nature as to facilitate locking and unlocking by one who is familiar with the operation. The key is so constructed that it need be merely lifted as far as it will go in order to release the first tumblers. The rotation of the cylinder then quickly puts it in position where the key is operative to retain the additional tumblers in unlocking position and the cylinder may be moved outwardly. The structure works easily and

the locking and unlocking are accomplished in but a moment of time. 55

Another object of the invention is the provision of parts adapted to retain the shackle in locked position despite the application of considerable force to the shackle. 60

Additional objects are simplicity of construction and ease of manufacture.

With the above and other objects in view, which will appear as the description proceeds, my invention resides in the novel construction, combination and arrangement of parts, substantially as hereinafter described and more particularly defined by the appended claims, it being understood that such changes in the precise embodiment of the herein disclosed invention may be made as come within the scope of the claims. 70

In the accompanying drawing, I have illustrated one complete example of the physical embodiment of the present invention constructed according to the best mode I have so far devised for the practical application of the principles thereof, and in which:

Figure 1 is a central, vertical, sectional elevation longitudinally through the lock, 80 and

Figures 2, 3, 4, and 5 are cross sections thereof on the lines 2—2, 3—3, 4—4 and 5—5, respectively, of Figure 1.

The casing 10 is provided with a chamber 11 adapted to receive an arm of shackle 12 having an enlarged head 13 thereon which may be moved freely through the chamber 11, retained at one end thereof by reason of the reduced diameter of the chamber, the casing fitting about the arm of a shackle to permit rotation of the arm when the device is unlocked, but to retain the shackle securely. The other arm of the shackle is adapted to be received in opening 14 in the casing and is provided with a slot to receive a tooth 15 carried by block 16, which fits in opening 17. The block is rectangular in cross section, as shown in Figures 1 and 2, so as to prevent rotation thereof in the casing, which fits closely about the block on all sides except the front. 95

The block is provided with a pin 17 having a narrowed end 18 adapted to be received in a groove 19 in cylinder 20, whereby the cylinder and block are retained together, the cylinder fitting snugly in the block, but prevented from separation by 100 105

means of the pin 17'. The series of upper tumblers 21 are provided in recesses in casting 10, urged downwardly by springs 22, the ends of which abut against plugs 23. 5 Lower tumblers 24 are, also, provided, urged upwardly by springs 25. Cylinder 20, as shown in Figures 1 and 5, is provided with an additional slot 26 extending annularly about the cylinder and backwardly a 10 short distance, as shown at 27, terminating short of the end of the cylinder, as is apparent from examination of Figure 1, in which the slot is indicated in dotted lines. 15 A pin 28 having a narrowed end 29, which is received in slot 26, maintains the cylinder 20 in inner position when the device is locked. The longitudinal portion of the slot, however, receives end 29 when the device is being unlocked and permits the forward movement of the cylinder. Cylinder 20 is provided with a keyhole 30 adapted to receive key 31. The inner end of the keyhole is closed by an end member 32 secured in position by a pin 33. To unlock the 25 device, key 31 is inserted into the keyhole 30, the key being provided with a groove 34 adapted to receive a laterally projecting pin 35. This groove directs the key properly. 30 When the key reaches its innermost position, limited by shoulders 36, it is lifted upwardly, a branch groove 37 permitting upward movement of the key, pin 35 being received in the branch groove. The upward movement of the key is limited by the upper edge thereof and at its limit of movement the tumblers 21 are lifted by bits 38 so as to lie along the surface of cylinder 20. 35 The cylinder may then be rotated substantially 180°. After the rotation of the cylinder for half a circle, tumblers 24 are free to enter the recesses in the cylinder. They are ejected by a downward movement of key 31, the bits 38 contacting with the tumblers. In this 40 position, narrowed end 29 is in registry with the longitudinal part of slot 26 so that the key may be moved outwardly drawing the cylinder with it, the limit of movement of the cylinder being determined by the dimension of the slot. The outward movement of the cylinder carries, also, block 16 and tooth 15, which releases shackle 12 permitting it to move outwardly to unlocked position. 45 To again lock the device, the shackle is moved substantially to the position shown in Figure 1 and the key and cylinder are moved inwardly carrying block 16 therewith. Bits 38 are urged downwardly to expel tumblers 24 which are urged into the recesses in the cylinder 20. The rotation of the cylinder by the key permits tumblers 21 to be again reinserted into the recesses in the cylinder, so that the parts are entirely in locking position. 50 It will be apparent, therefore, that the

device is exceedingly difficult to operate to one not knowing the principle of operation thereof, but that it may be operated easily and quickly by one familiar with its working. 70

I claim:—

1. The combination of a casing, a shackle pivoted thereto and having a transversely slotted locking end, said casing having an opening to receive the locking end of said shackle, a series of slidable spring urged tumblers within said casing, a cylinder provided with a key slot and a series of apertures adapted to receive said tumblers, said cylinder being rotatably mounted within said casing, a slidable block operably coupled to said cylinder and having a tooth adapted to enter the slot in the locking end of said shackle, and a key adapted to enter the slot within said cylinder and to press the tumblers outwardly from the recesses in said cylinder, whereby when the key is inserted the cylinder may be rotated and moved axially to withdraw the tooth from engagement with the slot in said shackle. 80 85

2. The combination of a casing having a plurality of aligned recesses, a tumbler in each of said recesses, a plurality of additional aligned recesses out of line with said first mentioned recesses, a tumbler in each of said additional recesses, a shackle having one end thereof rotatably secured to said casing, the other end of said shackle having a slot therein, a block, a tooth carried by said block adapted in locking position to be received in said slot, a cylinder having recesses adapted to receive said tumblers, said casing having an opening receiving said cylinder, said cylinder having a keyhole therein, and a key adapted to be received in said keyhole and to be moved laterally therein to expel said tumblers. 100 105

3. The combination of a cylinder having a longitudinal hole therein, a pin secured to said cylinder projecting laterally into said hole, said cylinder having a plurality of recesses therein, a plurality of tumblers, movable in said recesses and a key having a slot therein, said key being adapted to be inserted into said hole and said slot being adapted to receive the end of said pin, said slot having a branch to permit lateral movement of said key to expel said tumblers. 110 115

4. In a lock the combination of a casing, a cylinder revolvably and slidably mounted therein and having an annular slot, a block having a locking tooth thereon, a pin secured to said block and slidably positioned within said annular recess, and a shackle having an end provided with a slot adapted to receive said locking tooth, said casing having a recess for said block. 120 125

5. In a lock the combination of a casing, a first and second set of spring pressed tumblers arranged in two spaced series, a 130

- longitudinally slotted cylinder having apertures for the successive reception of said first and second set of tumblers, said cylinder being revolvably and slidably mounted within said casing, a block revolvably joined to said cylinder and slidably carried by said casing and having a locking tooth, a shackle having an end provided with a slot for the temporary reception of said tooth, and a key
- having a flat body adapted to enter said slot 10 and having bits adapted to depress one series of plungers at a time and to engage said cylinder.
- In testimony that I claim the foregoing I have hereunto set my hand at Milwaukee, 15 in the county of Milwaukee and State of Wisconsin.

ADAM PRIMAK.
